UNITED STATES PATENT OFFICE

FRANK DITCHFIELD, OF CLEVELAND, OHIO, ASSIGNOR TO THE YOUNGSTOWN STEEL CO.
DOOR COMPANY, OF CLEVELAND, OHIO, A CORPORATION OF OHIO

GRAIN DOOR FOR CARS

Application filed September 24, 1930. Serial No. 434,032.

This invention relates to improvements in grain doors for cars, the present application constituting a continuation in part of my co-pending application Serial No. 5 478,645, filed August 29, 1930 for improvements in grain doors for cars.

As well known to those skilled in the art, there has long been a demand for a satisfactory permanent type of grain door for 10 box cars and numerous attempts have been made to supply this demand. The most common arrangement heretofore suggested has involved the use of a main panel or door section pivoted at its outer edge adjacent the side door sill, which main section or panel, when not in use as a grain door, becomes a part of the car floor. Due to limitations in the width of the car, such main sections or panels cannot be made of 15 the necessary height to close the side door opening and in order to provide for the additional height necessary when the door is in operative position, it has been customary to provide a pivoted or slidably connected auxiliary or supplemental flap or section attached to the inner or free edge of the main door section. In such constructions, the auxiliary or supplemental sections 20 have always heretofore been folded under or disposed under the main door section or panel when the latter is in the horizontal inoperative floor position. Further, so far as I am aware, all such main door sections have heretofore been made of wood, presumably to conform to the remaining wood 25 floor of the box car.

The types of grain doors above referred to have not proven satisfactory in service, particularly because the main wood door 30 section or panel has its upper surface exposed when lying in the horizontal floor position and is thus subjected to wear and distortion on its upper surface. It is this upper surface of the main door section which 35 must be placed against the door posts, fillers or car lining and door sills, in order to provide the necessary grain seal and because of the distortion and wear occurring on such surface, proper seals cannot be maintained after such doors have been in ser-

vice for any length of time, thus permitting leakage of the grain, as will be apparent.

While the auxiliary or supplemental door sections are housed or protected in the former types of such grain doors, their importance is considerably less than that of the main door section, the auxiliary or supplemental section being intended primarily to prevent spilling over of the grain. It will further be obvious that with the former 55 types of such grain doors, the use of metal in the exposed portions, lying in the floor position, is impracticable because of the indentation that would take place in the trucking in and out of the lading when the car is 60 used for other purposes than that of carrying grain.

Another condition of practical importance in the use of grain doors is connected with the means for initially relieving the pressure of the grain behind the grain door before the latter can be opened or displaced. Where such grain doors are used in a box car having a discharge hopper opposite the door opening, no so-called relief doors are 75 necessary but in cars of the non-hopper type, relief doors are necessary and difficulty has heretofore been experienced in protecting such relief doors from injury.

One object of my invention is to provide 80 a grain door adapted to become a part of the floor section, when not in use as a grain door, so arranged that those surfaces used to effect sealing with the door posts, fillers or car lining, are not subject to wear or injury 85 while in the floor position, so that a proper and efficient sealing may always be maintained when the door is in operative position.

Another object of my invention is to provide 90 a grain door such that the main or lower portion thereof, which is subject to the maximum grain pressure, may be made of metal of relatively light weight but great 95 rigidity and so disposed, when not in use as a grain door, that it cannot be injured or distorted from moving of the lading thereover.

A further object of my invention is to 100 provide a grain door for box cars comprised

of sections pivotally connected to each other at one set of ends, the opposite end of one section being pivotally connected to the car adjacent the door sill and the opposite end 5 of the remaining section having a slidable guiding connection with the car side, so that both sections are always connected to the car body in any position thereof and their proper relation to each other and to 10 the car body thereby always maintained.

Another object of my invention is to provide a grain door for box cars of that type where the door is adapted to assume a position forming a part of the car floor, the 15 arrangement including a main section and an auxiliary section such that the auxiliary section acts as a protector or guard for the main section when the parts are in inoperative or floor position.

20 A still further object of my invention is to provide a foldable grain door for box cars, which, when in an inoperative floor position, will occupy the minimum depth, so as to avoid extending too far below the floor 25 level, where it might otherwise interfere with the usual brake rigging and other ap- purtenances necessarily disposed on the car beneath the floor.

Still another object of my invention is to 30 provide a grain door having incorporated therein a rugged and substantial relief door which is effectively guarded against injury in any position of the grain door proper and which may be readily operated to release 35 the grain from behind the grain door.

In the drawings forming a part of this specification, Figure 1 is a broken, vertical, 40 sectional view taken transversely of a box car having incorporated therein my improved grain door, the latter being shown in full lines in inoperative position and in operative position by dotted lines. Figure 2 is a broken part top plan view, part horizontal sectional view corresponding to the 45 section line 2—2 of Figure 1. Figure 3 is a longitudinal, vertical, sectional view corresponding to the line 3—3 of Figure 2. Figure 4 is a broken, enlarged front elevational view illustrating portions of the relief door and operating devices therefor. Figures 5 and 6 are enlarged, horizontal, 50 sectional views illustrating details of construction of the relief door and corresponding to the section lines 5—5 and 6—6 respectively of Figure 4. Figure 7 is an enlarged, vertical, sectional view illustrating 55 details of construction of the relief door. Figure 8 is an enlarged, vertical, detailed, 60 sectional view illustrating the guide connection for the auxiliary or supplemental door section when in inoperative position. And Figure 9 is a similar view illustrating the 65 guide connection when the supplemental section is in vertical operative position.

In said drawings, the box car is shown as having center sills 10—10 with a cover plate 11, channel side sills 12, needle beams 13 and wood flooring 14. The side of the car is or may be of the usual wood sheathing type, as indicated at 15, with a door opening defined by special track tie section posts 16 to the outer sides of which are secured angles 17. To the front angle 17 is secured an additional angle 18 functioning as a stop for the front edge of the usual outside door 19, the rear angle 17 having a special weather strip 20 secured thereto with which cooperates a corresponding weather seal element 21 attached to the vertical rear edge of the door 19. As shown in Figure 1, the top of the door opening is defined by a Z-bar lintel 22, to the outer depending flange of which is attached a smaller Z-bar 23, the latter functioning as a retaining guide for the upper edge of the door 19. The threshold of the door opening is formed by an angle bar 24 having a relatively short, vertically up-standing flange at its outer end and a longer, horizontally disposed flange secured to the top flange of the side sill 12. To the angle bar 24 is secured a special T 25, having an upper horizontal flange, as clearly shown in Figures 1 and 7.

In carrying out my invention, the car 25 is provided with a sheet metal sub-flooring 26 opposite each side door opening, said sub-flooring being preferably corrugated, as indicated at 27, and having its inner edge supported on the cover plate 11 and its outer edge resting on the horizontal flange of the angle 24. The side edges of the sub-flooring panel 26 are upwardly sloped, as indicated in Figure 3, and supported on special rolled elements 28—28 which extend 105 from center sill to side sill, said elements 28 each having an upstanding flange 29 seated within a recess 129 in the flooring 14 so as to provide a grain seal between the sub-floor 26 and the wood floor of the car. 110

For each side door opening of the car, I provide a grain door which comprises two sections A and B, the former being what I term the lower or main section of the grain door and the latter the supplemental or auxiliary section of the grain door. Said main section A, as shown, is comprised of sheet metal which may be made of relatively light gauge and weight and yet obtain the necessary strength to resist the fluid-like pressure of the grain or other similar type of lading. As shown, said main section A consists of a panel of sheet metal having a plurality of integrally formed corrugations 30—30 formed therein, said corrugations being so disposed that when said section A is in horizontal position, as best shown in Figure 1, the corrugations nest with respect to the corrugations 27 of the sub-floor 26. With this nested formation of the main door 130

section and sub-floor, it is evident that the total depth from the lower plane of the sub-floor to the uppermost plane of the supplemental door section B when the grain door 5 is in inoperative position, is reduced to a minimum so as to avoid interference with any brake rigging or other attachments usually applied to the car beneath the floor. Said main door section A has flat marginal 10 flanges 31—31 (see Figure 3), which are adapted to lie flat against the inner flanges of the special section door posts 16, when the main door section A is in vertical operative position, to thereby form a grain seal 15 with the posts 16. Said main section A also has a flat front marginal portion 32 adapted to seat against the inner edge of the sill angle 25 (except where inwardly offset to accommodate the relief door hereinafter 20 scribed), to form with the sill angle a grain seal along the bottom of the door. The main door section A is pivotally connected to the fixed portions of the car by hinge butts 33 in turn pivotally connected to hinge 25 brackets 34, the latter being mounted in the space provided by the sill structure composed of the two angles 24 and 25, as best 30 shown in Figures 1 and 7.

The supplemental door section B, as shown, is comprised of a series of wood planks suitably bound at their inner ends by an angle binding strip 35 and at their outer ends by another angle binding strip 36. The supplemental section B is pivotally connected to the main section A by three 35 hinges 37—37 (see Figure 2), the hinge connection being disposed outwardly of the inner edge of the supplemental door section B as the latter is viewed in Figure 1 in inoperative position. By this arrangement, when the two sections A and B are raised to vertical operative position, as shown by dotted lines in Figure 1, the then lower edge 40 of the supplemental section B will overlap the then upper edge of the main section A and on the inner side of the latter so as to provide a seal preventing leakage of the grain through the joint. The supplemental door section B is of such contour and area 45 that it completely covers the main door section A when in floor or inoperative position, said supplemental section B forming a flush continuation of the fixed portions of the wood flooring of the car. When in vertical 50 operative position, it is evident that the side edges of the supplemental door section B will also fit snugly against the inside flanges of the door posts 16 and form a grain seal therewith.

Referring particularly to Figure 2, it will be noted that the special track tie sections, forming the post 16, are so constructed as to provide vertical channels on either side of the central web thereof and I make use 55 of this construction in providing for a slid-

able guiding connection for the free edge of the supplemental door section B in the movements of the latter. Referring to Figures 2, 8 and 9, I pivotally attach to the supplemental door section B, adjacent each side thereof, near the outer edge, an angular lever 38, each of said levers 38 at the outer end of its arm having journaled thereon a preferably tapered guide roller 39, which rollers work within the channels provided by the posts 16. When the supplemental door section B is in horizontal inoperative position, the roller carrying lever or bracket 38 assumes the position shown in Figure 8 but, as the section B is elevated to operative position, the roller carrying lever 38 swings about its pivotal connection with the section B until it assumes the position shown in Figure 9. With this arrangement, it is evident that a connection is always maintained between the free edge of the supplemental door section B and the car side and, because of the pivotal mounting of the roller carrying arms or levers 38, compensation is automatically obtained for the arcuate path necessarily taken by the outer edge of the door section B in its movements from operative to inoperative position and vice versa, while at the same time maintaining proper guiding connection with the posts.

To hold the door sections A and B in vertical position and against accidental inward movement before the grain load is applied therebehind, slide bolts 40—40 may be mounted on the supplemental door section B flush with or below the surface thereof, which bolts, when the door sections are in vertical operative position, may be projected behind the adjacent flanges of the door posts 16, as will be understood.

As is well known to those skilled in the art, it is highly desirable that the pressure of the grain on the grain door be relieved before the grain door is opened to discharge the car. Certain railways prefer to employ a discharge hopper in connection with the sub-floor for this purpose, which hopper may be opened to empty the grain immediately behind the grain door. Many other railroads prefer a relief door in the grain door proper and in order to meet the requirements of both classes of railroads, I have provided a novel and efficient type of relief door C in the main door section A. Near the bottom of the main section A and centrally thereof, I cut out the metal so as to leave a rectangular relief door opening 41, which is defined by part of the flat marginal flange section 32, flat side flanges 42 and upper horizontal flange 43, the latter being shown best in Figures 5 and 7. Along each vertical side of the opening 41, the sheet metal door section A has an inwardly pressed vertically extending corrugation 44 to accommodate certain parts of the operat-

ing mechanism for the relief door C, and along the lower portions of the side edges of the relief door opening 41 the main sheet metal door section A is corrugated, as indicated at 45, to give additional strength and also to provide a grain seal with the relief door C, as will be evident from inspection of Figure 6.

The relief door C is, as shown, made of sheet metal and has an upper inwardly sloping top flange 46, vertical section 47 and a lower vertical section 48 offset from the section 47, as indicated at 49. Along its vertical edges, the relief door C is formed with a wide corrugation 50, (see Figure 6) with a marginal flange 51, the sectional contour being changed toward the upper part of the relief door C to that shown in Figure 5 where the marginal flange 151 is extended 20 farther inwardly so as to seat within the corrugated portion 44 of the main door section A. With the construction shown and described, it is evident that a grain seal is thus provided between the relief door and main door section A around all four edges of the relief door.

The relief door is adapted to be operated with respect to the main door section A in the following manner. Near the top of the relief door C and at each side thereof is secured a bracket casting 52 having an up-standing arm 53. Pivotally mounted on the main door section A in three spaced bearing brackets 55 is an operating shaft 54 to the ends of which are secured two operating levers 56. The latter are of the bell crank form, each having an offset crank pin or stud 57 pivotally connected to the upper ends of the arms 53 so that, when the levers 56 are swung from their normal vertical position downwardly to the dotted line position shown in Figure 7, a combined vertical and slight outward movement will be imparted to the relief door C. In the normal closed position of the relief door C, as shown in full lines in Figure 7, the lower flat portion 48 thereof will bear against the inner edge of the door sill angle 25 and extend somewhat below the latter. As the levers 56 are swung in the manner above referred to, the relief door C will be elevated sufficiently for the lower edge of the latter to clear the door sill angle 25 whereupon, the pressure of the grain therebehind will automatically swing the relief door outwardly to the dotted line position shown in Figure 7, and permit discharge of enough of the grain behind the grain door proper to relieve the latter of pressure and permit of its being opened.

After the grain is cleared away from the relief door, the latter will tend to swing back to vertical position which in turn will swing the operating levers 56 upwardly to a more nearly vertical position. As the grain door

proper is folded and moved to floor position, the supplemental section B will swing down over both the operating levers 56 and the relief door so as to insure their proper return with respect to the main section A 70 when the parts assume the full line position shown in Figure 1. To accommodate the operating levers 56, the supplemental door section will be rabbeted or recessed, as indicated at 58.

Various changes and modifications may be made in the details of construction and all such changes are contemplated as come within the scope of the claims appended hereto.

I claim:

1. In a car having a door opening, a grain door movably attached to the car adjacent the sill of the door and movable to both vertical operative position to close the lower portion of the door opening and a horizontal inoperative floor position; a relief door pivotally mounted on said grain door and bodily movable therewith; and displaceable floor-forming means for covering and protecting said grain door and relief door when the grain door is in said inoperative floor position.

2. In a car having a door opening, a grain door pivotally attached to the car adjacent the sill of the door and movable to both vertical operative position to close the lower portion of the door opening and a horizontal inoperative floor position; and a relief door slidably and pivotally mounted on said grain door and bodily movable therewith; and manually operable means mounted on the grain door for imparting sliding movement to the relief door when the grain door is in vertical operative position.

3. In a car having a door opening, a grain door movably attached to the car adjacent the sill of the door and movable to both vertical operative position to close the lower portion of the door opening and a horizontal inoperative floor position; and a relief door movably attached to said grain door in such position that the lower edge of said relief door engages behind the door sill when said grain door is moved to vertical operative position.

4. In a car having a door opening, a grain door movably attached to the car adjacent the sill of the door and movable to both vertical operative position to close the lower portion of the door opening and a horizontal inoperative floor position; and a relief door pivotally attached along its upper edge to said grain door and so positioned that, when the grain door is moved to vertical operative position, the lower edge of the relief door engages behind and is held by the door sill.

5. In a car having a door opening, a sheet metal grain door movably attached to the car adjacent the sill of the door and mov-

able to both vertical operative position and horizontal inoperative floor position; and a sheet metal relief door pivotally attached to the outer side of and bodily movable with 5 the grain door, the two doors having overlapping portions with cooperable seal-forming indentations therein.

6. In a car having a door opening, a grain door comprising a main section and a supplemental section pivotally connected thereto, said main section being pivotally attached to the car adjacent the door sill, said sections being movable to vertical operative position and collapsible to folded inoperative floor position with the supplemental section on top of the main section; a relief door mounted on said main section; and an operating mechanism for said relief door also mounted on the main section.

20 7. In a car having a door opening, a grain door movably attached to the car adjacent the door sill and movable to vertical operative position and horizontal inoperative floor position; a relief door pivotally and 25 slidably attached to said grain door; and manually operable means associated with the relief door for sliding the latter and permitting pivotal movement thereof, said means including a lever and link connection 30 between the lever and relief door.

8. In a car having a door opening, defined in part by a door sill with a space therebeneath, a grain door pivotally attached along one edge in said space beneath 35 the sill and movable to a vertical operative position with the lower portion engaging the sill; and a relief door movably mounted on said grain door on the outer side thereof, said relief door having its lower portion normally confined between the door sill and grain door when the latter is in vertical operative position.

9. In a car having a door opening, a grain door movably attached to the car adjacent 45 the door sill and movable to vertical operative position and horizontal inoperative floor position; supplemental grain door means adapted to assume an inoperative floor position on top of said grain door; a 50 relief door on said grain door; and operating means for said relief door, said relief door and operating means being housed by said supplemental door means when the latter is in inoperative floor position.

55 10. In a car having a door opening, a grain door comprising a main sheet metal section and a supplemental section pivotally connected thereto, said sections being adapted to assume a vertical operative position 60 and a folded inoperative floor position, said main section being pivotally attached to the car adjacent the door sill; a sheet metal relief door pivotally and slidably mounted on said main section near the outer pivoted 65 edge of the latter; operating means for said

relief door mounted on the main section, said relief door being so positioned that when the main section is in vertical operative position the lower free edge of the relief door is initially held by the door sill and adapted 70 to be elevated by the operating mechanism to clear the sill and permit outward pivotal movement thereof.

11. In a car having a door opening and a floor, the combination with vertical guides 75 extending adjacent the side edges of the door opening; of a main door section movably attached along its outer edge to the car adjacent the door sill and adapted to assume a vertical operative or a horizontal inoperative floor position; a supplemental door section pivotally connected to the opposite edge of said main section; and cooperable means on the outer free edge of said supplemental section movably attached thereto and cooperable with said guides, the supplemental door section overlying and protecting the main section when the sections are in said inoperative floor position.

12. In a car having a side door opening, 80 a side sill with a top horizontal flange, and a door sill including an angle member with a flange disposed horizontally and spaced above said side sill flange; of a grain door; and means, mounted within the space between said flanges for pivotally attaching the grain door and adapting the door to swing to either horizontal floor position or vertical operative position with the lower portion thereof adjacent said door sill 85 flange, whereby said pivot-attaching means are housed and protected from injury when the lading is being transported through the door opening.

13. In a car having a side door opening 90 and a side sill therebeneath, the combination with an angular member mounted on top of the side sill; of a T member secured to said angular member, the flanges of the T forming the door sill and spaced above the side sill; a main grain door section pivotally attached to the car in the space beneath the door sill flange and adapted to assume either a vertical operative position or a horizontal inoperative position; a supplemental grain door section pivotally connected to the free edge of said main section and adapted to fold thereover when in inoperative horizontal floor position, the upper surface of said supplemental section, when in 100 inoperative position, being flush with the door sill flange.

14. In a car of the box car type having a side door opening defined by fixed elements of the car body, the combination with a grain door displaceable to and from an operative position, closing the lower portion of the door opening, said grain door having a relief opening therein; and a relief door for closing said relief opening, the relief 105

door being pivotally attached along one of its edges to the outer side of the grain door and adapted to swing outwardly from pressure of grain on the inner side of the grain door, the free edge of the relief door being so positioned that, when the grain door is in operative closing position, said free edge is normally engaged and retained between the grain door and one of said fixed elements defining the side door opening.

15. In a car having a side door opening, the combination with a sheet metal grain door adapted to assume a vertical operative position over the lower portion of the side door opening and an inoperative floor position, said grain door having a relief opening therein; of a sheet metal relief door adapted to close said relief opening, and combined attaching and operating means for 20 said relief door including a manually operable shaft oscillatably mounted on the grain door, said shaft having a crank arm extension and an element secured to the relief door pivotally connected to said crank arm 25 extension.

16. In a car having a door opening defined in part by metal side posts each having a channel facing the door opening, said channels extending below the floor level, the 30 combination with a grain door comprised of an upper and a lower section pivotally connected along their adjacent edges; of means pivotally connecting the lower edge of the lower door section to the car below 35 the floor level; and means pivotally and slidably connecting the upper door section to the door posts, said means including devices extending within and cooperating with said post channels and adapted to move to a position 40 in said channels below the floor level when the lower door section is pivotally swung inwardly of the car and the two sections pivotally fold on each other.

In witness that I claim the foregoing I
45 have hereunto subscribed my name this 20th
day of September, 1930.

FRANK DITCHFIELD.
